(57) CLAIM

The ornamental design for a tote bag, as shown and described.

DESCRIPTION

FIG. 1 is a front elevational view of a tote bag showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front, left, and top perspective view thereof; and,

FIG. 8 is a rear, right, and top perspective view thereof.

The broken lines in the figures are included for the purpose of illustrating portions of the tote bag that form no part of the claimed design.

1 Claim, 8 Drawing Sheets
